UNITED STATES PATENT OFFICE.

JOHN WILLIAM COOPER, OF KINGSTON-UPON-HULL, ENGLAND.

COLLAPSIBLE BOX, PACKING CASE, AND THE LIKE.

Application filed December 6, 1921. Serial No. 520,249.

To all whom it may concern:

Be it known that I, JOHN WILLIAM COOPER, a subject of the King of Great Britain, residing at Kingston-upon-Hull, in the county of York, England, have invented certain new and useful Improvements in Collapsible Boxes, Packing Cases, and the like, of which the following is a specification.

This invention has reference to boxes, 10 packing-cases and the like and especially those made of wood.

My invention has for its primary object the production of a box or packing-case which can be collapsed and folded up when 15 not in use, and when folded up will only occupy a small space when being stored or when being carried as an empty on railways, in ships and the like.

A further object is to provide boxes and 20 cases of the kind mentioned with means for so securing the lid of the box or case in position when the box or case is in use that such lid cannot be removed without the fact being quickly detected.

25 With these and other objects in view the invention consists in the novel combination and arrangement of parts hereinafter described, illustrated in the accompanying drawings and pointed out in the claims hereunto appended, it being understood that various changes in the form of some of the parts and in minor details of construction within the scope of the claims may be resorted to without departure from the spirit 30 or sacrificing any of the advantages of the invention.

In the accompanying drawings, Fig. 1 is a 35 perspective view of a shallow box embodying my invention but with the lid removed, Fig. 2 is a plan view of the box body, and Fig. 3 is a perspective view of the lid. Fig. 4 is a perspective view of the box body partly folded, and Fig. 5 is a view of it folded or closed up and the lid in position. Fig. 40 6 is an end view of a portion of the box body, a portion of the metal top corner of the end piece being broken away to show the means for connecting such end and the adjoining side piece when in their perpendicular position. Fig. 7 is a vertical section of the vertical leaf 45 of one of the hinges by which one end piece of the box is hinged to the box bottom, provided with the pivoted eye which forms a part of the means for securing an end piece to a side piece, Fig. 8 is a front view of the

same. Fig. 9 represents one end of one end piece and portion of the bottom of the box body and shows the opening in the metal corner of the end piece to receive the eye on the side portion and the pin which passes through such eye to secure the said end and side portions in their upright position, Fig. 10 is a section of one corner of the box on the line $\alpha-\alpha$ of Fig. 6. Fig. 11 is a perspective view of a deep box showing one of the sides provided with double hinges to allow it to fold under the side opposite to it and one of the other sides with hinges suitable to allow it to fold over the side opposite to it, Fig. 12 is a side view of a portion 70 of the box showing in dotted lines two of the sides folded over the bottom of the box, Fig. 13 is a view of the adjoining side of the same showing in dotted lines the other two sides folded under the box bottom, and Fig. 14 is an end view of a portion of a box showing a means for preventing the metal depending members of the box lid from being forced out of the holes in the end of the box, which they engage.

45 Referring to the drawings, A indicates the bottom of the box, B and B^1 are the two ends of the box which are so hinged to the bottom A that they will fold over such bottom, and C, C^1 are the two sides of the box and which are so hinged to the said bottom A that they will fold under such bottom b , b^1 indicating the hinges of the two ends B, B^1 and c , c^1 the hinges of the two sides C and C^1 . The leaves of the hinges which are secured to the side piece C, C^1 extend up the outside 50 of the said side pieces and have each a projection c^2 formed according to a convenient mode by making a suitably shaped cut in the leaf and pressing inwardly the piece of metal within the cut. These projections pass into slot-holes c^3 in the side pieces of the box, and to each of such projections is pivoted a flat metal piece c^4 provided at its outer end with a hole, these metal pieces being adapted to be turned sideways into the slot-holes c^3 when the box is folded up.

55 The top corners of the two end pieces B, B^1 of the box are cut away and hollow metal corner pieces D are substituted therefor, each corner piece being provided with an aperture d in its outer end or edge, and with a hole in its top into which hole is inserted a pin d^1 provided with a suitable head or enlarged top, the said pins securing the ends 60

and sides of the box together in their upright position when, the box is opened out for use, by passing through the holes in the projections c^4 pivoted to the projections c^2 5 on the vertical leaves of the hinges c, c^1 by which the side pieces C, C^1 of the box are hinged to the box bottom A.

In the case of a box the ends and sides of which, if the box is an oblong one, or the 10 four sides of which if it is a square one, are of such a height that when folded those which fold over the box bottom would not lie in the same plane and those which fold under such bottom would not lie in the 15 same plane, if hinged in the ordinary way, I provide one of the ends or sides as the case may be, which fold over the box bottom, with hinges the joint of each of which instead of being at the juncture of such end or 20 side with the bottom of the box, is at a point a suitable distance above the bottom of the box as indicated at b^2 Figs. 11, 12 and 13 of the drawings, whereby such end or side will fold over and lie in the same plane as the 25 opposite end or side, and in the case of the ends or sides which fold under the bottom of the box, I provide the hinges of one of such ends or sides with a supplementary joint as indicated at c^6 in Figs. 11 and 13 of the 30 drawings, whereby such end or side will fold under and will lie in the same plane as the opposite end or side. E, E are two metal eyes secured to the end piece B of the box and which project above the top of such 35 end, and F, F are two slot-holes in the end B^1 of the box.

G indicates the lid of the box which is provided at one end with two metal depending members g, g^1 which have inwardly turned 40 bottom ends, and at its other end with two holes g^2, g^3 .

To fit the lid on the open box body, the inwardly turned bottom ends of the depending members g, g^1 fitted to one end of such 45 lid are inserted in the two slot-holes F, F in one end or side piece, as the case may be, of the box body, and the lid lowered on to the open top of the box body when the eyes E, E secured to the opposite end or side of 50 the box body will project upwardly through the holes g^2, g^3 in the lid. A rod H is then passed through the eyes E, E, the said rod being suitably enlarged at one end h to prevent it from being pulled through such eyes 55 in one direction and being provided at the other end with an eye through which can be passed the hinged shackle of a padlock, or a cord or the like to the two ends of which a lead or like seal h^1 can be applied 60 to prevent the withdrawal of the rod by an unauthorized person, or if such rod is withdrawn, rendering it necessary to remove the padlock or the seal so enabling the fact that the rod has been tampered with to be readily 65 detected.

To prevent the metal depending members g, g^1 of the lid from being pried out of the slot-holes F, F in the end B^1 of the box body whereby the lid could be raised at that end and access be gained to the contents of the 40 box, without removing the rod H, I may provide the end or side B^1 of the box body with eyes J, J preferably formed integral with plates J^1, J^1 secured by preference to the inside of such end B^1 , which eyes pass 45 through holes in the end of the box and through correspondingly situated holes formed in the metal depending members g, g^1 on the lid, through which eyes J, J I pass a rod K the said rod being suitably enlarged 50 or formed at one end to prevent it from being pulled through the eyes in one direction, and being provided at the other end with an eye to take the hinged shackle of a padlock, or to take a cord or the like to the two ends 55 of which a lead or the like seal h can be applied, see Fig. 14 of the drawings.

When the box is to be folded or closed up, the lid is removed, the two end pieces and the two side pieces, or the two pairs of side 60 pieces as the case may be, of the box body, depending upon the box is an oblong one or a square one, are turned or folded the one pair over the box bottom and the other pair under such bottom and the depending metal 65 members g, g^1 fitted to one end of the lid are passed on to one end or side of the folded body and their inturned bottom ends project under and engage the two side pieces or one of the end pieces folded under the box 70 bottom, the lid itself lying flat on the side or end pieces which are folded over the said box bottom, the lid being secured in position by pieces of cord or the like passed through the holes g^2, g^3 in such lid and through other 75 holes which could be provided for the purpose in the corresponding end of the box bottom, or by a cord or cords passed around the folded box, or by any other convenient means as will be readily understood. 80

What I claim and desire to secure by Letters Patent is:—

1. In a box, packing-case or the like, a bottom piece, two end pieces so hinged to the two ends of such bottom piece as to be 85 adapted to fold over the same, and two side pieces so hinged to the said bottom piece as to be adapted to fold under the same, the two side pieces being provided with pivoted eyes and the two end pieces with metal box-like corners each having an aperture to receive the pivoted eye on the adjoining side piece, and with a pin to pass into such eye to secure the end and side pieces together in their perpendicular position to form the 90 open box, case or the like.

2. In a box, packing-case or the like, a bottom piece, two end pieces so hinged to the two ends of such bottom piece as to be adapted to fold over the same, and two side pieces 100

so hinged to the said bottom piece as to be adapted to fold under the same, the two side pieces being provided with pivoted eyes and the two end pieces with metal box-like corners each having an aperture to receive the pivoted eye on the adjoining side piece, and a pin to pass into such eye to secure the end and side pieces together in their perpendicular position to form the open box, case or the like, eye pieces secured to one end piece and projecting above the top of the same and two slot-holes in the opposite end piece.

3. In a box, packing-case or the like, a bottom piece, two end pieces so hinged to the two ends of such bottom piece as to be adapted to fold over the same, and two side pieces so hinged to the said bottom piece as to be adapted to fold under the same, the two side pieces being provided with pivoted eyes and the two end pieces with metal box-like corners each having an aperture to receive the pivoted eye on the adjoining side piece, and a pin to pass into such eye to secure the end and side pieces together in their perpendicular position to form the open box, case or the like, eye pieces secured to one end piece and projecting above the top of the same, two slot-holes in the opposite end piece, a lid provided with metal depending members having inturned bottom ends, fitted at one of its ends, and two holes at its opposite end, a rod adapted to pass through the eyes which pass through the holes in one end of the lid when the lid is in position on the open box body, the said rod having one end enlarged or suitably formed to prevent it from being drawn through the said eyes and being provided with an eye at the other end to take the hinged shackle of a padlock, or a cord or the like to the two ends of which a lead or like seal can be applied, eyes carried by one end of the box body, the said eyes passing through holes in the downwardly projecting metal members fitted to the corresponding end of the lid, when the lid is in position on the open box body, and a rod adapted to pass through such eyes, the said rod having one end enlarged or suitably formed to prevent it from being drawn through the said eyes and having an eye at its other end to take the hinged shackle of a padlock, or a cord or the like to the two ends of which a lead or like seal can be applied.

4. In a box, packing-case or the like, a

bottom piece, two end pieces so hinged to the two ends of such bottom piece as to be adapted to fold over the same, and two side pieces so hinged to the said bottom piece as to be adapted to fold under the same, the two side pieces being provided with pivoted eyes and the two end pieces with metal box-like corners each having an aperture to receive the pivoted eyes on the adjoining side piece and a pin to pass into such eye to secure the end and side pieces together in their perpendicular position to form the open box, case or the like, eye pieces secured to one end piece and projecting above the top of the same, two slot holes in the opposite end piece, a lid provided with metal depending members having inturned bottom ends, fitted at one of its ends, and two holes at its opposite end, a rod adapted to pass through the eyes which pass through the holes in one end of the lid when the lid is in position on the open box body, the said rod having one end enlarged or suitably formed to prevent it from being drawn through the said eyes and being provided with an eye at the other end to take the hinged shackle of a padlock, or a cord or the like to the two ends of which a lead or like seal can be applied, eyes carried by one end of the box body, the said eyes passing through holes in the downwardly projecting metal members fitted to the corresponding end of the lid, when the lid is in position on the open box body, and a rod adapted to pass through such eyes, the said rod having one end enlarged or suitably formed to prevent it from being drawn through the said eyes and having an eye at its other end to take the hinged shackle of a padlock, or a cord or the like to the two ends of which a lead or like seal can be applied.

In testimony whereof I affix my signature.

JOHN WILLIAM COOPER.
